George A. Landon, Inventor:
By his Attorneys,

C. Snow & Co.

UNITED STATES PATENT OFFICE.

GEORGE ARTHUR LANDON, OF TORONTO, CANADA, ASSIGNOR OF ONE-HALF TO WILLIAM DOUGLAS, OF SAME PLACE.

NECK-YOKE.

SPECIFICATION forming part of Letters Patent No. 605,490, dated June 14, 1898.

Application filed September 7, 1897. Serial No. 650,841. (No model.)

To all whom it may concern:

Be it known that I, GEORGE ARTHUR LANDON, manufacturer, a subject of Her Majesty Queen Victoria, residing in the city of Toronto, in the county of York, in the Province of Ontario, Canada, have invented certain new and useful Improvements in Neck-Yokes, of which the following is a specification.

The invention relates to improvements in neck-yokes.

The object of the present invention is to improve the construction of neck-yokes and to provide a simple, strong, and durable one designed to be readily applied to an ordinary pole or tongue and adapted to accommodate itself to any movement of a pair of horses and at the same time be capable of retaining its position on a pole or tongue should a trace or traces become accidentally broken, and thereby prevent runaways and other accidents often resulting from neck-yokes becoming detached from poles or tongues.

The invention consists in the construction and novel combination and arrangement of parts, as hereinafter fully described, illustrated in the accompanying drawings, and pointed out in the claim hereto appended.

In the drawings, Figure 1 is a perspective view of a neck-yoke constructed in accordance with this invention and shown applied to a pole or tongue. Fig. 2 is a vertical sectional view taken transversely of the neck-yoke. Fig. 3 is a detail perspective view of the neck-yoke center.

Like letters of reference designate corresponding parts in the several figures of the drawings.

A designates a pole or tongue, and B a neck-yoke, which is provided at its ends with metal loops b, receiving straps C, which are attached to the front harness of the horses.

The neck-yoke has attached to its lower face a ball-socket D, constructed of malleable metal or other suitable material and provided at the top with laterally-extending flanges D', having perforations d, through which pass bolts E, which extend through the neck-yoke, and a top plate F, located on the

upper face of the neck-yoke and situated diametrically opposite the socket.

The socket D, which is provided at its rear side with a slot d', receives a solid ball G, which is provided with a stem passing through the slot d'. The slot d', which forms a way for the stem of the bar, extends from the top 55 of the socket to the bottom of the central portion of the same.

The stem, which inclines upward and rearward, is formed integral with a ring G², which is obliquely arranged on the pole or tongue 60 in alinement with the stem and the ball and abutting against the metal stop.

The invention has the following advantages:

The neck-yoke center is simple and comparatively inexpensive in construction and is adapted to be readily applied to a neck-yoke and a pole.

It will be clearly understood that if either one of the horses attached to the neck-yoke moves forward ahead of the other the neck-yoke will swivel on the ball-joint without danger of any strain or breakage. Should it be desired to back, the neck-yoke will always swing backward, so that the socket will be 75 tilted rearwardly upon the ball and the slot moved downwardly upon the stem. In case of accident, such as the breakage of a trace or traces, it will be seen that immediately the horse freed will exert its strain upon the ball 80 and socket, bringing the stem against the lower portion of the slot and having a tendency to cant the ring forwardly at the top and cause the same to bind effectually upon the pole, thereby securing the neck-yoke to 85 the pole and thus preventing any danger of running away. The driver is also enabled to draw up his horses and repair the damage.

What I claim is—

The combination with a neck-yoke, and a pole, of a ring arranged on the pole and provided with an upwardly-extending rearwardly-inclined stem formed integral with the ring, a solid ball arranged at the upper end of and formed integral with the stem and being of much greater diameter than the same,

and a socket receiving the ball and provided at its back with a narrow slot receiving the stem and extending downward from the top of the socket to the center of the bottom portion thereof, said socket being provided at its top with a flange D' secured to the lower face of the neck-yoke, substantially as described.

Signed at Toronto this 7th day of July, 1897.

GEORGE ARTHUR LANDON.

In presence of—
BOSVILLE PLACE,
LENA MCARTHUR.
